The ornamental design for a headrail for pleated and cellular shades, as shown and described.

DESCRIPTION

FIG. 1 is a perspective view showing the top, front and right side of the headrail for pleated and cellular shades;

FIG. 2 is a top view thereof;

FIG. 3 is a bottom view thereof;

FIG. 4 is a front view thereof, the rear view being a mirror image thereof;

FIG. 5 is a right end view thereof; and,

FIG. 6 is a left end view thereof.

The claimed design is shown fragmented to indicate indeterminate length.
